UNITED STATES PATENT OFFICE.

MIKOLAJ SMARLIN, OF KEWANEE, ILLINOIS.

PUMP.

1,200,995.

Specification of Letters Patent. Patented Oct. 10, 1916.

Application filed May 6, 1914. Serial No. 836,782.

To all whom it may concern:

Be it known that I, MIKOLAJ SMARLIN, a citizen of the United States of America, residing at Kewanee, in the county of Henry and State of Illinois, have invented 5 certain new and useful Improvements in Pumps, of which the following is a specification, reference being had therein to the accompanying drawing.

10 This invention relates to pumps, and has for its object to provide a device of such class, in a manner as hereinafter set forth, for lifting water to various levels for use for any purposes desired.

15 Further objects of the invention are to provide a pump which is comparatively simple in its construction, operated in a convenient manner, readily set up, strong, durable, efficient in its use, and comparatively inexpensive to manufacture.

20 With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come 25 within the scope of the claim hereunto appended.

30 In the drawings wherein like reference characters denote corresponding parts throughout the several views: Figure 1 is a side elevation of a pump in accordance 35 with this invention, Fig. 2 is a sectional elevation illustrating the adaptation of the pump with respect to a water storage receptacle and with respect to a discharging nozzle, Fig. 3 is a vertical sectional view of 40 a pump, and Fig. 4 is a vertical sectional view taken at right angles to Fig. 3.

45 Referring to the drawings in detail, 5 denotes a reservoir provided with a body of water 6 and said reservoir 5 is closed by a cover 7 having a centrally disposed opening 8. Arranged within the reservoir 5 is a support 9 for the pump, which is referred to generally by the reference character 10. 50 The pump 10 has apertured ears 11 for the purpose of securing said pump 10 to the support 9.

55 The pump includes a casing 12, open at one side and the said open side is closed through the medium of a closure plate 13. The casing 12 is provided with socket form-

ing members 14, against which abut apertured ears 15, through which extend hold-fast devices 16 for detachably connecting the plate 13 in position.

60

The closed side of the casing 12 is formed with a centrally disposed opening 17 and further provided with an outwardly projecting bearing 18. The plate 13 is provided centrally with an opening 19 and 65 with an outwardly projecting collar 20, and is provided with peripheral threads. Arranged within the casing 13 is a shaft 21, having each end reduced as at 22, 23. The reduced end 22 is of less diameter than 70 the reduced end 23 and the said reduced end 23 is journaled in the opening 17 and bearing 18. The reduced end 23 projects through the opening 19 and collar 20, and has its free terminus squared as at 24. Surrounding the reduced end 23 is a packing 75 25, which is maintained in position by a packing gland 26. Fixed upon the squared terminus of the reduced end 23 is a crank arm 27, formed with a longitudinally extending slot 28. The casing 12 is provided with an integral V-shaped web and the arms of the latter are indicated at 29, 30 and the apex at 31, the latter being cut away to provide a bearing surface 32. 80 Each of the arms 29 and 30 is formed with an opening 32a and the said arms 29, 30 in connection with said casing 12 and plate 13 provide an outlet chamber 33.

85 The inner face of the casing 12, at the 90 bottom thereof is formed with an integral enlargement 34 provided with a segment-shaped passage 35. Formed integral with the enlargement 34, centrally thereof, is a web 36, which is positioned in a plane to 95 intersect centrally the V-shaped web. The free end of the packing gland 26 is spaced from the aperture of the V-shaped web and is rounded as at 37 to provide a bearing surface.

100 The shaft 21 rides against the bearing surfaces 32 and 37, and has formed integral therewith a pair of oppositely disposed piston members 38, 39, the latter extends between one side of the enlargement 34 and 105 the arm 30, and the former extends between the other side of the enlargement 34 and the arm 29. The piston members 38 and 39 travel against the inner face of the casing 12 and the member 38 in connection with the 110 arm 30 provides a pumping chamber 40, and the member 39 in connection with the arm

28 provides a pumping chamber 41. The end 42 of the passage 35 opens into the inlet chamber 41, and the end 43 of the passage 35 opens into the pumping chamber 40. The member 38 as well as the member 39 is provided with a pumping opening and the pumping opening for the chamber 40 is indicated at 44 and the pumping opening for the chamber 41 is indicated at 45. The openings 33^a are outlets for the chambers 40 and 41.

Pivots connected to the member 38, as at 46, is a flap valve 47 for closing the inlet 44 and pivots connected to the member 39, as at 48, is a flap valve 49 for closing the inlets 45. Pivots connected as at 50 and 51, to the enlargement 34, are oppositely disposed flap valves 52 and 53 respectively for alternately closing the ends 42 and 43 of the passage 35. Formed integral with the casing 12 and depending therefrom is an inlet nipple 54, which opens into the passage 35 centrally thereof, and has connected thereto a depending pipe 55, which extends into the body of water 6 and has a screened lower end 56. The pipe 55 is termed an inlet pipe. Arranged within the outlet chamber 33 is a butterfly valve 57 for alternately closing the openings 32, and communicating with said outlet chamber 33 is an outlet 58 arranged in alignment with a discharge nipple 59, which is connected to a service pipe 60. Communicating with the discharge nipple 59 are oppositely disposed drain passages 61, having outlets 62. The service pipe 60 extends up through the opening 8, and is provided with a valve 63 and a nozzle 64. Communicating with the service pipe 60 is a branch service pipe 65 having a valve 66. The pipe 65 extends up into a receptacle 67, and is provided with a nozzle 68 for supplying water 69 to the receptacle 67 when the valve 66 is open and the suction members 38 and 39 operated. The receptacle 67 has a valve outlet 70. Extending through the opening 8, and pivots connected to the service pipe 60, as at 71, is an operating member 72, the latter having a handle 73 at its upper end, and at its lower end is slidably connected by the pin 74 to the crank 27. The pin 74 extends through the slot 28.

When the member 72 is oscillated, the crank 27 is operated in a like direction and which causes an oscillatory motion of the shaft 21. When the shaft 21 is oscillated,

the members 38 and 39 are operated in alternate directions to cause an alternate supply of water to the chamber 40 and 41. When the member 38 moves downwardly, the valve 47 is open and the water passes through the inlet 44 into the chamber 40. The downward movement of the member 38 causes the closing of the valve 53. Under such conditions the supply of water through the end 43 of the passage 35 to the chamber 40 is discontinued. When the member 38 moves downwardly, the member 39 moves upwardly, causing the valve 52 to open and a supply of water to enter the chamber 41 through the end 42 of the passage 35. When the member 39 moves upwardly, the valve 49 is caused to close the opening 45, and the water in the chamber 41, above the member 39 is forced through the opening 42 in the arm 29 into the chamber 33. When the water is forced into the chamber 33, through the opening 32 in the arm 29, it causes the butterfly valve to shift in the chamber 33 to close the opening 32^a in the arm 30. The water passes from the chamber 33 through the outlet 58 into the discharge nipple 59, from whence it is conducted by the service pipe to the point desired.

What I claim is:

A pump comprising a casing provided with a discharge chamber having a pair of outlets, a butterfly valve within said chamber for alternately closing said outlets, a pair of pumping chambers, valve piston members operating in opposite directions for alternately forcing water in one of said pumping chambers into said discharge chamber, valve means for alternately controlling the supply of water to said pumping chambers, means for establishing communication between said casing and a water supply, an oscillatory shaft for operating said piston members, an arm pivoted to a service pipe and secured to said oscillatory shaft to operate the same, oppositely disposed drain passages surrounding the periphery of said pump chamber and means for conducting the water from said discharge chamber.

In testimony whereof I affix my signature in the presence of two witnesses.

MIKOLAJ SMARLIN.
